COMBINATION AIRSHIP AND AEROPLANE

Filed Feb. 29, 1928

FIG. 1.

FIG. 2.

INVENTOR:

PETER ARNDT,
By: *Allen H. Ringer,
his Atty.*

UNITED STATES PATENT OFFICE.

PETER ARNDT, OF LOS ANGELES, CALIFORNIA.

COMBINATION AIRSHIP AND AEROPLANE.

Application filed February 29, 1928. Serial No. 257,967.

This invention relates to flying-machines of the heavier than air type which makes use of gas-carrying facilities.

One of the objects of this invention is to provide longitudinally disposed planes designed to embody cabins.

Another object is to arrange cabins within a plane.

Another object is to provide a gas-holding structure in combination with transversely and longitudinally disposed planes.

Another object is to arrange transversely disposed carrying planes between the gas-holding structure and the cabin-holding lower planes.

Other objects will appear from the following description and appended claims as well as from the accompanying drawing, in which—

20 Fig. 1 is a side elevation of a combination airship and aeroplane structure embodying this invention.

Fig. 2 is a front elevation of the combination structure illustrated in Fig. 1.

25 According to the principal feature of this invention, a fuselage is eliminated and a portion of the plane structure is hollow and designed to hold cabins for passengers and other requirements.

30 The longitudinally disposed portions of the planes are preferably utilized for this purpose.

As illustrated in the drawing, the longitudinally disposed plane portion is arranged in the lower part of the combination structure. This longitudinally disposed plane portion is in form of transversely arched portions 3 and 4, forming two longitudinally disposed air channels 5 parallel to the longitudinal axis of the whole structure. This longitudinally disposed plane structure is of a suitable thickness in order that its hollow space may be utilized for cabins and other purposes commonly arranged in a fuselage.

45 This longitudinally disposed plane structure is firmly connected to transversely disposed plane structures 6 and 7 by means of upright, comparatively narrow passageway structures 8.

50 Above the transverse planes 6 and 7 a gas-holding structure 9 is arranged and interconnected with the plane structures.

Motors 10 are provided at various suitable points in the whole structure.

55 This invention provides a structure which facilitates a slow and comfortable landing

by means of the gas-carrying structure 9.

The whole arrangement assures a high degree of safety since the comparatively large, transversely disposed planes 6 and 7 are between the gas-holding structure 9 and the cabin-carrying plane structure 3—4.

In an emergency case it is possible to maintain this structure in the air even if the gas-carrying structure should explode or otherwise be damaged. Plane structures 3—4 and 6 and 7 are of sufficient size to assure proper carrying surfaces without the gas structure 9.

Especially the longitudinally disposed plane structure 3—4 is intended to provide 70 a suitably large carrying surface in addition to the carrying surfaces of the transversely disposed planes 6 and 7.

Having thus described my invention, I claim:

1. In a structure of the class described, a longitudinally disposed plane structure, transversely disposed plane structures spaced above and connected to the first-named plane structure, and a gas-holding structure spaced 80 above and connected to the previously named plane structures.

2. In a structure of the class described, a cabin-embodying longitudinally disposed plane structure, transversely disposed plane structures spaced above and connected to the first-named plane structure, and a gas-holding structure spaced above and connected to the previously named plane structures.

3. In a structure of the class described, a cabin-embodying longitudinally disposed plane structure, transversely disposed plane structures spaced above and connected to the first-named plane structure, and a gas-holding structure spaced above and connected to the previously named plane structures, and comparatively narrow upright passageway structures between the cabin-embodying plane structure and the transversely disposed plane structures adapted to form the communicating means therebetween.

4. In a structure of the class described, a cabin-embodying longitudinally disposed plane structure, transversely disposed plane structures spaced above and connected to the first-named plane structure, a gas-holding structure spaced above and connected to the previously named plane structures, and driving means at suitable points of the structure.

In testimony that I claim the foregoing as 110 my invention I have signed my name.

PETER ARNDT.
